UNITED STATES PATENT OFFICE.

SETH W. BABBITT, OF MERIDEN, CONNECTICUT.

BUTTER-DISH.

SPECIFICATION forming part of Letters Patent No. 259,075, dated June 6, 1882.

Application filed March 23, 1882. (No model.)

To all whom it may concern:

Be it known that I, S. WILLIAM BABBITT, a citizen of the United States, residing at Meriden, in the county of New Haven and State 5 of Connecticut, have invented certain new and useful Improvements in Butter-Dishes; and I do hereby declare the following to be a full, clear, and exact description of the invention, such as will enable others skilled in the 10 art to which it appertains to make and use the same.

My invention relates to improvements in butter-dishes; and the object is to improve their construction in such a manner that access 15 can be had to the interior without entirely removing the cover or revolving it into a recess below, as has been done.

The invention consists in hinging the cover or top at one side of the base or main body 20 of the butter-dish, so that the said cover can be turned up to expose the interior, and access can be had to its contents without taking it off entirely, all of which will be more fully described hereinafter, reference being 25 had to the accompanying drawings and the letters of reference marked thereon.

Like letters refer to like parts in the figures of the drawings, in which—

Figure 1 is a rear elevation of my improved 30 butter-dish. Fig. 2 is a side elevation of the same, with the cover shown raised in dotted lines.

In the drawings, A represents the base or main body of a butter-dish, which may be of 35 any desired configuration, and ornamented in the most elaborate manner, if desired. It is provided with handles B and the usual knife-holder, C, upon which the butter-knife is supported. At the rear side of the base or lower 40 part, A, are arranged in any suitable manner two lugs, *a b*, which form the stationary part of the hinge D, to which the cover is pivoted. The cover E is also made of highly ornamental shape, and is provided with lugs *c d*, forming 45 the movable part of the hinge D. Suitable screws, *e*, which are secured into the lugs *a b*, form the pivots upon which the cover rotates when it is desired to gain access to the dish, making about a quarter of a revolution, and said 50 cover is supported with its lower edge upon the sides or edges of the lower part or base

A. The usual drainer is arranged in the ordinary manner in the base, and a handle on the top of cover serves to manipulate it by.

I do not confine myself to the exact style 55 and form of hinge shown in the drawings, as this may be varied to suit the various styles of butter-dishes. For instance, the lugs may be extended backward and a pin or bolt passed through both without deviating from the spirit 60 of my invention.

The principal point of my invention is the placing of the hinges upon the base or lower part of the butter-dish and pivoting the cover to them, so as to gain access to the dish without removing the cover entirely or revolving it. Another important feature is that, the 65 cover being hung eccentrically, the inner edges thereof bear against the sides of the base when in its upright position, and the 70 base thus forms the stop for the cover.

The advantages in securing and arranging the cover in the manner herein shown and described will be readily appreciated by all conversant with them, and among some of them 75 may be mentioned that by not removing the cover and laying it on the table-cloth it will not become soiled; persons are more liable to cover the dish again and prevent flies from alighting on the butter than when the cover 80 is to be taken up and replaced; the cover is not so liable to stick or become out of order as when revolved into a receptacle below, which is the case with the revolving covers now in use; the parts can be easily and readily 85 cleaned, and are not liable to get out of order; the device is simple in construction, and, if desired, can be readily applied to butter-dishes now in use without much additional expense, and it can be easily repaired in case 90 any part becomes worn out.

Having thus described my invention, what I claim, and desire to secure by Letters Patent, is—

1. A butter-dish having the cover hinged at 95 one side to the main body or base of the dish, substantially as shown and specified.

2. A butter-dish having the cover pivoted to one side of the base of the dish by hinges arranged substantially as shown, and for the 100 purpose described.

3. A butter-dish having the base A provided

base A provided with lugs *a b*, and the cover E with lugs *c d*, and screws *e* to form hinges, arranged substantially as and for the purpose set forth.

4. The butter-dish herein described, consisting of the base A, having lugs *a b*, in combination with a cover, E, provided with lugs *c d*, and the screws *e*, arranged at one side of the said dish, substantially as shown and specified.

5. In butter-dishes, the manner herein described of hinging the cover eccentrically to the base and forming a stop for the cover by the edges of the base, substantially as shown and specified.

6. In a butter-dish, the cover hinged eccentrically to the base, the edges of which form a stop for the cover when in its upright or open position, substantially as set forth.

In testimony whereof I hereby affix my signature in presence of two witnesses.

SETH WILLIAM BABBITT.
